US0D1079161S

(12) **United States Design Patent** (10) **Patent No.:** **US D1,079,161 S**
(45) **Date of Patent:** **** Jun. 10, 2025**

(54) **HANDHELD CORDLESS VACUUM
CLEANER**

(71) Applicant: **HZSamko Technologies Co., Ltd.**,
Hangzhou (CN)

(72) Inventor: **Lingliang Ma**, Hangzhou (CN)

(73) Assignee: **HZSamko Technologies Co., Ltd.**,
Hangzhou (CN)

(**) Term: **15 Years**

(21) Appl. No.: **29/917,981**

(22) Filed: **Nov. 23, 2023**

(30) **Foreign Application Priority Data**

Oct. 7, 2023 (CN) 202330643886.1

(57) **CLAIM**

The ornamental design for a handheld cordless vacuum cleaner as shown and described.

DESCRIPTION

FIG. 1 is a perspective view of a handheld cordless vacuum cleaner, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown are included for the purpose of illustrating portions of the handheld cordless vacuum cleaner which form no part of the claimed design.

1 Claim, 8 Drawing Sheets
